[57] **CLAIM**

An ornamental design for a handgrip for electronic game control pad, as shown and described.

DESCRIPTION

FIG. 1 is a perspective view of a handgrip for electronic game control pad showing our new design;

FIG. 2 is a left side elevational view thereof; the right side elevational view being a mirror image thereof;

FIG. 3 is a bottom plan view thereof;

FIG. 4 is a top plan view thereof;

FIG. 5 is a front elevational view thereof; and,

FIG. 6 is a rear elevational view thereof.

FIG. 1

FIG. 2

FIG. 3

FIG. 4

FIG. 5

FIG. 6
